UNITED STATES PATENT OFFICE.

GUSTAV L. JAEGER, OF NEW YORK, N. Y.

BRONZING-MACHINE.

SPECIFICATION forming part of Letters Patent No. 242,932, dated June 14, 1881.

Application filed April 28, 1881. (No model.)

To all whom it may concern:

Be it known that I, GUSTAV L. JAEGER, a citizen of the United States, residing at New York, in the county and State of New York, have invented new and useful Improvements 5 in Bronzing-Machines, of which the following is a specification.

This invention relates to machines for applying bronze-powder or the like to paper or other 10 similar material; and it consists in certain novel combinations of a sheet - carrying cylinder, a bronze-hopper, and a wiping-apron, as herein-after fully described, and pointed out in the claims.

15 This invention is illustrated in the accompanying drawings, in which Figure 1 represents a vertical section taken in the plane of the line $x x$, Fig. 2. Fig. 2 is a plan or top view. Fig. 3 is a vertical section on the line $y y$, Fig. 20 1, showing the bronze-hopper and its concomitants.

Similar letters indicate corresponding parts.

The letter A designates the sheet-carrying cylinder, B the bronze-hopper, and C the continuous stretched wiping-apron.

25 The cylinder A is provided with a griper, D, (one or more,) which is operated by cams 5 in the usual manner to grasp the sheet to be bronzed, thereby carrying it around the cylinder, and release it at the appropriate place.

30 The bronze-hopper B is located opposite to the surface of the cylinder A, at any suitable place above the axis thereof to deposit the bronze on the sheet that is being carried around the cylinder, the hopper being in this example directly above the cylinder, and at the bottom of the hopper is arranged a sliding gate, F, to which a reciprocating motion is imparted at intervals, as hereinafter described, thus intermittently opening and closing the hopper.

35 The wiping-apron C is arranged in superficial contact with the cylinder A, beginning at a point beyond the bronze-hopper B and extending a distance about equal to one-half the circumference of the cylinder, and the upper end of the apron is secured to a cross-piece, 6, of the machine-frame, while the lower end extends over a roller or bar, 7, and is provided with a weight, 16, for keeping the apron in a 40 taut condition. In lieu of the weight 16 a winding roller may be used. I make the wiping-

45 apron C preferably of plush-cloth, placing the nap against the surface of the cylinder. By its arrangement the wiping-apron C is kept in a stretched condition and stationary in a longitudinal direction. A reciprocating motion, 50 however, is imparted to the apron in a lateral direction, and by this means the bronze deposited on the sheet by the hopper is spread or distributed crosswise, as well as lengthwise, 55 of the sheet as the latter is drawn between the cylinder and the apron. The apron C being arranged to extend around the larger portion of the periphery of the cylinder A, and being retained in a stretched condition, and 60 therefore uniformly pressing on the surface of the cylinder, it will be evident that the bronze is evenly and uniformly distributed on the paper throughout its entire surface in a much more perfect manner than where bronze is distributed by reciprocating independent pads or 65 brushes.

70 For the purpose of imparting the desired motion to the wiping-apron C, I make use of trip-cams 8 and 9, which project from the cylinder 75 at one end and act on rigid cross-pieces 10, secured to the apron, in the revolutions of the cylinder, and of springs 15, (see Fig. 2,) the cross-pieces being bent at one end toward the cylinder, as at 11, and these bent ends being in the 80 path of the cams. If desired, the trip-cams 8 9 may be arranged at both ends of the cylinder, the cams at one end acting alternately with those at the other end.

85 The gate F is perforated and slides directly beneath the bottom 12 of the hopper, which is perforated in a similar manner to the gate, and the means employed for operating the gate consists of the trip-cam 9, (this being one of the cams for operating also the wiping-apron,) 90 which acts directly on the gate in the revolutions of the cylinder, at one end of the gate, and of a spring, 13, Fig. 3, the gate being bent toward the cylinder, as at 14, to bring the same into the path of the cam. By the action of the 95 cam 9 the gate is forced against the spring 13, and its perforations are caused to register with those in the bottom 12 of the hopper, thus allowing the bronze to discharge, while, when the action of the cam ceases, the perforations 100 are immediately brought out of registration with each other by the action of the spring.

If desired, the cam 9 may be made adjustable, and by this means the movement of the gate D can be varied to allow a greater or less amount of bronze to escape from the hopper.

5 For the purpose of catching the surplus bronze a box or receptacle, G, is arranged around the cylinder and apron.

It should be remarked that instead of giving a laterally-reciprocating motion to the wiping-apron C this motion may be imparted to the cylinder with a like result, and also that other mechanism than that described may be used for accomplishing the desired purpose—as, for example, the cylinder may be provided with a 15 serpentine cam-groove to engage the rigid cross-pieces or any other suitable part of the apron.

The advantage peculiar to the trip-cams 8 9 is that one of such cams serves also to operate 20 the hopper.

I am aware that it is not new, broadly, to combine a wiping-apron with a sheet-carrying cylinder, and also that laterally-reciprocating brushes have been used in connection with an 25 endless sheet-carrying apron; and such not being within the scope of my invention, I hereby disclaim the same.

A bronzing-machine has heretofore been constructed of a bronze-hopper arranged above a 30 sheet-carrying drum provided with clamps for grasping a sheet of paper on the feed-table, and a series of independent brushes or pads reciprocated across the cylinder for spreading the bronze on the paper; but such does not 35 constitute my invention, and is not claimed by me.

The hopper of a bronzing-machine has also been provided with a slide reciprocated by cams and springs across the discharge-mouth 40 of the hopper for intermittently feeding the bronze; and such, broadly, I do not claim.

What I claim as new, and desire to secure by Letters Patent, is—

1. The combination, substantially as hereinbefore set forth, of the sheet-carrying cylinder, the continuous stretched wiping-apron arranged in superficial contact with the cylinder, and mechanism for imparting to the wiping-apron or the cylinder a reciprocating motion, for the purpose set forth.

2. The combination, substantially as hereinbefore set forth, of the sheet-carrying cylinder, the bronze-hopper located opposite to the surface of the cylinder, the wiping-apron arranged in superficial contact with the cylinder, and mechanism for imparting to the wiping-apron or the cylinder a reciprocating motion, for the purpose described.

3. The combination, substantially as hereinbefore described, of the sheet-carrying cylinder having trip-cams at one or both ends, the continuous stretched wiping-apron arranged in superficial contact with the cylinder, the rigid cross-pieces of the apron, having their ends arranged in the path of the trip-cams, 65 and the springs acting on the cross-pieces, for the purpose described.

4. The combination, substantially as hereinbefore set forth, of the sheet-carrying cylinder having the trip-cam 9 directly attached to its 70 end, the bronze-hopper located opposite to the surface of the cylinder, and having a bottom, 12, provided with perforations, the sliding gate F, provided with a series of perforations, and having its end arranged in the path of the 75 trip-cam, and the spring acting on the gate, for the purpose described.

5. The combination, substantially as hereinbefore set forth, of the sheet-carrying cylinder having the trip-cams 8 9, the continuous 80 stretched wiping-apron arranged in superficial contact with the cylinder, the rigid cross-pieces of the apron, having their ends arranged in the path of the trip-cams, the springs acting on the cross-pieces, the bronze-hopper located opposite to the surface of the cylinder, the sliding gate of the bronze-hopper, having its end arranged in the path of the trip-cam 9, and the 85 spring acting on the gate, for the purpose described.

In testimony whereof I have hereunto set my hand and seal in the presence of two subscribing witnesses.

GUSTAV L. JAEGER. [L. S.]
